By his Attorneys,

James I. Dawson,
Inventor

C. Howles.

UNITED STATES PATENT OFFICE.

JAMES L. DAWSON, OF TUSCOLA, ILLINOIS.

INDICATOR.

SPECIFICATION forming part of Letters Patent No. 445,271, dated January 27, 1891.

Application filed August 12, 1890. Serial No. 361,804. (No model.)

To all whom it may concern:

Be it known that I, JAMES L. DAWSON, a citizen of the United States, residing at Tuscola, in the county of Douglas and State of Illinois, have invented a new and useful Indicator, of which the following is a specification.

The invention relates to improvements in indicators.

10 The object of the present invention is to provide an indicator having a list of household articles, groceries, and current necessities, and convenient means for indicating those articles of the list which are needed.

15 A further object of the invention is to provide a perpetual calendar and arrange the parts to afford space for advertising.

20 The invention consists in the construction and novel combination of parts hereinafter fully described, illustrated in the accompanying drawings, and pointed out in the claims hereto appended.

25 In the drawings, Figure 1 is an elevation view of an indicator embodying the invention. Fig. 2 is a sectional view on line *x x* of Fig. 1. Fig. 3 is a similar view on a line *yy* of Fig. 1. Fig. 4 is a detail view of the T-shaped bar. Fig. 5 is a similar view of one of the sliding pointers, and Fig. 6 is an enlarged detail view of the T-shaped bar.

30 Referring to the accompanying drawings, I designate an indicator card or board provided near each vertical side with two columns 2 and 3, containing a list of the various articles occasionally needed about a house. Secured to the card 1 and arranged between the columns is a bar 4, upon which slide pointers 5, extending out upon opposite sides of the bar and adapted to be arranged opposite the names of the various articles needed in the columns 2 and 3. The bar 4 is constructed of sheet metal bent longitudinally to form a top flange 6, and a web 7 to provide a T-shaped bar 4, and the pointer 5 is provided 45 at its inner end with a loop 8, having an opening 9 in its lower side adapted to receive the web 7 of the bar and allow the loop to embrace the flange 6 and slide thereon to bring

the pointer opposite any one of the names in the list. The pointer is held opposite a name, 50 and is prevented accidentally slipping therefrom by a spring-tongue 10, formed integral with the pointer by sliding the metal of the loop, and the said spring-tongue is adapted to engage the outer face of the bar. The 55 sheet metal at the edge of the web 7 is bent outward parallel with the flange 6 to form a bearing or inner face for the bar, and the latter is provided at intervals with integral portions 11, which are passed through kerfs 12 of 60 the board or card and bent against the rear face of the latter to secure the bar in place.

The upper portion 13 of the space between, with sets of columns, is designed to be used for advertising and the lower portion is provided with a perpetual calendar 14, consisting of the usual table 15 of days and an endless band 16, arranged in parallel slots 17 of the board or card 1, and adapted to expose a portion of its surface, and having marked 70 thereon the names of the days of the week, which are arranged in series. There are seven different sets of names, each commencing with a different day, thereby enabling the calendar to be adjusted for any month in any 75 year.

The top of the indicator card 1 is provided with a perforation 18 to enable the indicator to be conveniently hung upon a nail or the like. 80

What I claim is—

1. An indicator comprising a card having the lists or columns of names 2 and 3 arranged in pairs, the bar constructed of sheet metal and bent to form the top flange 6 and 85 the web 7, and provided at intervals with the integral portions 11, adapted to be passed through the card and bent against the same for securing the bar in place, and a sliding pointer arranged upon the bar, substantially 90 as described.

2. An indicator comprising a card having the lists or columns, the T-shaped bar secured to the card and the pointer sliding on the bar and constructed of metal and provided with a 95 loop having the transverse opening to receive

the web of the bar and provided with the integral spring-tongue adapted to receive the bar, substantially as described.

3. An indicator comprising a card having the lists or columns, the bar secured to the card, and the pointer sliding on the bar and provided with the spring-tongue, substantially as described.

In testimony that I claim the foregoing as my own I have hereto affixed my signature in presence of two witnesses.

JAMES L. DAWSON.
